UNITED STATES PATENT OFFICE

2,635,027

DISH CABINET

Marie E. Rasmussen, Neola, Iowa

Application April 26, 1951, Serial No. 223,031

1 Claim. (Cl. 312—229)

1

This invention relates to dish-draining equipment and more particularly it is an object of this invention to provide an efficient dish-draining cupboard.

Another object of this invention resides in the provision of a cupboard as described which is provided with shelves in a manner for holding dishes apart from each other for efficient draining.

Another object of the invention is to provide a dish-draining cupboard having adjustable dish-supporting members which can be set for dishes of various sizes.

Still a further object of the invention resides in the provision of a dish-draining cupboard having grooves in the shelves thereof for conducting water away from dishes.

A particular object of the invention is to provide a cupboard as described the drain water of which is conducted to a single outlet which latter can be connected in any suitable manner to a drain.

Yet another object of the invention resides in the provision of a cupboard as described the shelves of which are inclined rearwardly from an entrance opening whereby dishes are prevented from falling out of the cupboard.

A further object of the invention resides in the provision of a dish-drainer cabinet the shelves of which can be made of corrugated material which is conventionally mass-produced at a low price.

Yet another object of the invention is to provide a device for the purpose described which is sturdy and durable in construction, reliable and efficient in operation, and relatively simple and inexpensive to manufacture, assemble and utilize.

Other and still further objects and advantages of the invention will become apparent from the following detailed description of a preferred embodiment thereof.

In the drawings:

Figure 1 is a front elevation of the dish-drainer of this invention, certain portions of a door employed being shown broken away and a dish disposed in one of the grooves of one of the shelves thereof being shown by dotted lines.

Figure 2 is a sectional view being taken substantially along the lines 2—2 of Figure 1 and looking in the direction of the arrows.

Figure 3 is a perspective view of the dish-drainer cabinet, the door thereof being shown in an open position.

Figure 4 is an enlarged top plan view of a corner portion of one of the corrugated shelves

2

of the invention showing the cut away portion of the shelf for permitting drain water to pass therethrough.

The dish-drainer cabinet of this invention includes an outer housing generally indicated at 10 having a back or rear wall 12, sides 14, top 16, and a front face 18. These portions are arranged in a box-like configuration the depth of the sides of which is slightly greater than the width of a conventional dinner plate, which latter is indicated at 19 in Figure 1.

The bottom 22 of the cabinet is inclined rearwardly from front to back and downwardly from right side to left side to a point of which an outlet pipe 28 is mounted, disposed in communication with the interior of the cabinet. A second bottom portion 30 forms one end of the bottom and the rearwardmost elongated side-to-side portion 32 of the bottom is inclined downwardly and at an angle with respect to the downward inclination of the largest bottom portion 32.

The cabinet 10 is preferably provided with a plurality of brackets 40 having screw apertures 42 as best seen in Figure 3. The brackets 40 are suitably secured to the upper sides of the cabinet.

The face or front wall 18 of the cabinet is provided with an opening 48 therethrough which is covered at times by a door 50 which latter has hinges 52, a handle 53 and a latch 54. The latch 54 is adapted to engage in a slot 58 in one side of the face 18 of the cabinet whereby the door 50 remains closed except at times when it is desired to open the door for the insertion of dishes.

The cabinet 10 is provided on each of its end walls 14 with a plurality of upright spaced apart rows of apertures 60 and the said rows are disposed in pairs, each pair being close to the other row of its same pair in a vertical direction but spaced apart in a horizontal plane therefrom.

The forwardmost row of a pair is disposed slightly above the rearwardmost row.

The rows of apertures 60 are for receiving the ends 62 of elongated upholding members or rods 66 which latter extend across the cabinet 10 from end to end in a horizontal plane. The members 66 are disposed in pairs each pair being arranged alongside each other and spaced apart forwardly and rearwardly of the cabinet with respect to each other. The ends of the elongated members 66 of a pair are disposed in corresponding pairs of rows of apertures 60 with respect to the elongated members 66 of the same pair.

The purpose of the members 66 is for upholding supporting members generally indicated at 70.

The members or shelves 70 are each generally

disposed in a single plane with an upward and a downward side. A plurality of grooves or corrugations 74 are provided in the upper sides of the members 70. The grooves 74 are disposed extending inwardly from the opening 48 and are preferably arranged in parallelism with each other.

The grooves 74 are for the purpose of receiving the lower edges of dishes, such as the dish 19, and conduct water from the dishes rearwardly of the cabinet. The grooves 74 preferably incline rearwardly and this is done by arranging the elongated member 66 upholding a supporting member 70 one above the other.

The members 70 are preferably formed of corrugated material of a type readily found on the market for the purpose of maintaining their cost at a minimum and their strength at a maximum.

The rearward ends of the grooves 74 are disposed in communication with cut-away portions or notches 78 of the members 70. The notches 78 are for the purpose of permitting drain water from the dishes to flow through the grooves 74 and downwardly through the cut-away notches 78 across the inclined bottom 22 to the outlet spout 28.

The cabinet of this invention will hold any amount of dishes in proportion to its size and can be placed on wheels if desired, can be hung on a wall, or can be positioned toward the back of a sink. The apertures or openings 60 in which rods 66 are not positioned provide vents through which air circulates to facilitate drying dishes on the shelves.

From the foregoing description it is thought to be obvious that a dish cabinet constructed in accordance with my invention is particularly well adapted for use by reason of the convenience and facility with which it may be assembled and operated, and it will also be obvious that my invention is susceptible of some change and modi-

fication without departing from the principles and spirit thereof and for this reason I do not wish to be understood as limiting myself to the precise arrangement and formation of the several parts herein shown in carrying out my invention in practice except as claimed.

I claim:

In a dish drying and storing cabinet, the combination which comprises a box-like housing having a bottom, a top, a rear wall, and end walls, a door hinged to one of said end walls providing a closure for the front of the housing, said bottom sloping to a low point and having an outlet pipe extended from said low point, said end walls having vertically spaced pairs of horizontally disposed openings therein, pairs of rods extended longitudinally through said housing and positioned with ends thereof in pairs of said openings, and corrugated dish carrying shelves positioned on said rods and formed with the corrugations therein extending from the front to the back of the housing, said pairs of openings in the end walls being positioned whereby the shelves are supported in inclined positions with the lower sides of the shelves at the back of the housing, and the low edges of said shelves having notches therein, said notches being positioned in the bottoms of troughs formed by said corrugations whereby water from dishes on the shelves drains through said notches.

MARIE E. RASMUSSEN.
